UNITED STATES PATENT OFFICE.

FRANK C. MARQUARDT, OF BROOKLYN, NEW YORK, ASSIGNOR TO AMERICAN BANK NOTE COMPANY, OF BROOKLYN, NEW YORK, A CORPORATION OF NEW YORK.

INKING MECHANISM FOR PRINTING MACHINES.

Application filed February 9, 1922. Serial No. 535,159.

To all whom it may concern:

Be it known that I, FRANK C. MARQUARDT, a citizen of the United States, residing at the borough of Brooklyn, in the city of New York, county of Kings, and State of New York, have invented certain new and useful Improvements in Inking Mechanisms for Printing Machines, of which the following is a specification, reference being had

10 to the accompanying drawings, which form a part thereof.

15 My invention relates to inking mechanisms for printing machines, and more particularly to an inking mechanism adapted to have movement in its entirety with relation to the form or plate cylinder, a construction requiring adjustment of the inking rollers in relation to the distributing roller, as well as to the form or plate upon the

20 cylinder.

25 Heretofore in mechanisms of the character to which my invention relates, adjustment means have been provided by which the inking rollers applying the ink to the form or plate have been capable of adjustment with relation to the distributing roller co-operating therewith by a movement substantially radially of said distributing roller, and of a rectilineal adjustment at an angle to a radius

30 of the form or plate cylinder.

35 With such mechanisms, during the make-ready of a press, considerable difficulty has been experienced in securing the proper adjustment of the inking rollers, since when such rollers are properly set as to the distributing roller, there was ordinarily a loss of such adjustment when subsequently adjusting the inking rollers to the plate upon the form or plate cylinder. This condition

40 required repeated trials and readjustments to secure a proper relation of the inking rollers to the form or plate, and also to the distributing roller co-operating therewith, and could be secured only by repeatedly

45 moving the carriage carrying the inking mechanism so as to bring the inking rollers into and out of engagement with the form or plate, and the exercise of a high degree of skill by the pressman.

50 With the above conditions in mind, I have provided an inking mechanism wherein adjustment for properly positioning the inking rollers with relation to the associated distributing roller, is such as to permit the

subsequent adjustment of said inking rollers 55 with relation to the printing surface upon the form or plate cylinder without disturbing in any way the previous adjustment of said rollers as to the distributing roller, thus permitting the main labor of accurate ad- 60 justment to be completed before the carriage is shifted so as to bring the inking rollers into engagement with the form or plate.

The construction is such that if necessary an inking roller may be adjusted with relation to the form or plate after the carriage or other support for the inking mechanism has been moved into the operative relation to the form or plate cylinder, means being provided whereby the supports for the bearings for the arbors of said inking rollers may be locked, or set, in any adjusted position so that thereafter the carriage may be moved freely toward and from the form or plate cylinder without the necessity for a 75 readjustment of said inking rollers.

When a plurality of inking rollers are employed, which is the usual condition, I provide means whereby they may be independently adjusted, thus ensuring the proper 80 positioning of each inking roller in the circular path of movement of the form or plate upon the cylinder.

The adjustment means above referred to co-operating with the inking rollers, may be 85 also utilized to develop and regulate the desired pressure by said rollers upon the printing surface.

The invention consists primarily in an 90 inking mechanism for printing machines embodying therein a carriage adapted to have movement toward and from a form or plate cylinder, a distributing roller mounted therein, an inking roller associated with said distributing roller and adapted to be 95 brought into and out of engagement with the form or plate upon said cylinder as determined by the movement of said carriage, means for imparting movement to said inking roller radially of said distributing roller to secure the proper relation of said rollers 100 to each other, and means for imparting movement to said inking roller circumferentially of said distributing roller, and towards or from said form or plate cylinder 105 to secure the proper relation of said inking roller to the form or plate, independently of said first named means; and in such other

novel features of construction and combination of parts as are hereinafter set forth and described, and more particularly pointed out in the claims hereto appended.

5 Referring to the drawings,

Fig. 1 is a side elevation of a portion of a carriage supporting the inking mechanism of a rotary press, showing a distributing roller and inking rollers associated therewith embodying my invention; and

10 Fig. 2 is an enlarged isometric view of one end of one set of inking rollers and their associated parts.

15 Like numerals refer to like parts in both of said views.

20 In the embodiment of my invention shown in the drawings, I employ two sets of inking rollers receiving ink from different founts through the usual sequence of cutting and distributing rollers. Each set of inking rollers and their associated parts, is an exact duplicate of the other, except as to minor changes of design, so that a description of but one set is essential.

25 The detailed construction of the carriage and the manner of moving same toward or from the impression cylinder is immaterial to my present invention, which merely contemplates such a movement aside from the mechanical expedients adopted in securing same.

30 In the drawings, I have shown at 10 a fragmentary portion of such a carriage omitting all of the distributing rollers except the one co-operating directly with the inking rollers, which distributing roller is shown at 11. The arbor of the roller 11 is mounted in bearings directly in the frame of the carriage 10 and has no movement in relation thereto. The inking rollers 12 and 13 are adapted to operatively engage the distributing roller 11 and to convey ink therefrom to the printing surface upon the form or plate cylinder indicated at 14.

40 Said inking rollers 12 and 13 are so mounted as to have movement radially of the distributing roller 11 to permit their adjustment to secure the proper co-relation between said rollers to insure the desired transfer of ink from the distributing roller to the inking rollers, said inking rollers also being adapted to be adjusted circumferentially of said distributing roller to permit their being brought into the proper inking relation to the form or plate upon the cylinder 14, without disturbing their adjustment with relation to the roller 11.

45 The above operative effect is secured by providing a bearing 15 for the inking roller 12 having a screw-threaded stem 16 slidably mounted in suitable bearings 17 and 18, said stem having an adjusting nut 19 mounted thereon intermediate said bearings so as to permit the bearing 15 to be moved toward and from the axis of the distributing roller

11 by a rectilineal movement radially of said axis.

The bearings 17 and 18 are carried by a frame 20 mounted to rotate or oscillate about an axis concentric with that of the 79 shaft of the roller 11, thus permitting the bearing 15 for the inking roller 12 to be moved circumferentially of said distributing roller 11, a movement which will not disturb the relation of the rollers 12 and 13 75 to the roller 11 as determined by the adjustment of the nut 19.

80 Slidably mounted in a lug 21 upon the carriage 10, is a screw 22 having mounted thereon adjustment nuts 23 and 24 arranged upon opposite sides of, and bearing upon, the lug 21. One end of this screw bears against the frame 20 so that rotary movement may be imparted to, or permitted in, said frame through the medium of the nuts 85 23 and 24 according to the direction of movement which it is necessary for the frame to have to bring the rollers 12 and 13 into the proper engagement with the form or plate upon the cylinder 14. 90

95 The screw 22 need not be, and in the form of the invention is not, directly connected with the oscillatory frame 20, since, as will fully appear hereinafter, under ordinary conditions said screw would serve merely as a limit stop to develop and define the desired pressure of the inking rollers upon the form or plate cylinder with the actuation of the carriage.

100 To permit the locking of the frame 20 in its adjusted position, I provide said frame with a segmental slot 25 therein through which passes a set screw 26 co-operating with the side frame of the carriage 10.

105 The arbors of the inking roller 13 are mounted in a closed bearing 27 instead of in an open bearing corresponding with the bearing 15, said bearing being adapted to have movement radially of the roller 11 through the medium of a screw 28 mounted in bearings 29 and 30 between which is mounted an adjusting nut 31. These bearings are carried by a frame 32 mounted to rotate or oscillate about an axis concentric with the axis of the shaft of the distributing roller 11, and with the axis of the frame 20, said frames 20 and 32 being mounted side by side as shown more clearly in Fig. 2. 110

115 The frame 32 has associated therewith an adjusting screw 33 mounted in a lug 34 carried by the carriage 10, said screw having mounted thereon a lock nut 35. The frame 32 is also provided with a segmental slot 36 corresponding in function with the slot 25 having associated therewith a set screw 37 corresponding in function with the screw 26.

120 While the details as to the adjusting screw 33, lug 34 and lock nut 35 differ from those of the screw 22, lug 21 and nuts 23 and 24, 125

130

the same operative effect is secured with both constructions. Consequently these details are immaterial to the invention when considered in its broader aspects.

5 The lower set of inking rollers and the associated parts shown in Fig. 1, is identical in construction and mode of operation with that above described; and corresponding reference numerals therefore are applied thereto without a further description of this 10 second inking mechanism, which, so far as this invention is concerned, may be used, or not, as desired.

15 The operation of the herein described mechanism is substantially as follows:—

The carriage 10 and the inking mechanisms carried thereby are moved away from the cylinder 14 during the makeready of a press to permit access to the form or 20 plate cylinder, or its associated impression cylinder not shown in the drawings, or during the run of a press, this carriage is sometimes moved away from the cylinder for the purpose of inspection or to permit 25 readjustment of the plate, or for other purposes.

During the makeready of the press, clean inking and distributing rollers are mounted in the machine, which involves proper adjustment of these rollers with relation to 30 each other as well as to the printing surface upon the form or plate cylinder.

In an inking mechanism made in accordance with my invention, the inking rollers 12 and 13 are first adjusted so as to be brought into the proper engagement with the associated distributing roller 11, by rotating the adjusting nut 19 or 31 to move the bearing 15 or 27 radially of the 35 roller 11 until the proper bearing contact is secured between the said inking rollers and the said distributing roller. When this adjustment is once secured, it is permanent to the extent that it is not disturbed by 40 subsequent adjustment of the inking rollers to secure the proper relation thereof to the printing surface upon the cylinder 14.

When this adjustment is secured, the 45 screws 22 and 33 are moved away from the frames 20 and 32 respectively and the set screws 26 and 37 are loosened, thus permitting freedom of rotary or oscillatory movement of the said frames about an axis concentric with that of the distributing roller 50 11 so that the inking rollers 12 and 13 may be moved to ensure their proper positioning with relation to the form or plate upon the cylinder 14 by a movement circumferentially of the distributing roller 11 without a loss 55 of the established contact relation between said inking rollers and said distributing roller.

When the parts are in this position, the carriage carrying the frame 10 may be 60 moved toward the cylinder 14, the final

movement of said carriage engaging the inking rollers 12 and 13 with the printing surface upon said cylinder.

The freedom of movement of the frame 20 will always be found to bring the roller 12 70 into engagement with the printing surface, although the roller 13 may not be so brought into such engagement. If it be necessary to adjust either roller 12 or 13 to secure the proper engagement thereof with said surface, this is secured by means of the screw 22 or 33 which is so actuated as to impart the desired movement to the frames 20 and 32 and of the inking rollers mounted therein respectively, circumferentially of the 75 roller 11, the arc of movement of said rollers causing them to approach, or permitting them to recede from, the cylinder 14, as determined by the direction of movement of said screws.

When the proper set of the inking rollers has been secured in the manner above described, the set screws 26 and 37 may be tightened so as to prevent subsequent movement of said frames with relation to the frame of the carriage 10 so that thereafter the carriage 10 may be so moved as to bring the inking rollers out of the operative relation with the printing surface without disturbing the adjustment, since upon restoration of said rollers to their operative position, their engagement with the printing surface will be the same under all conditions.

The adjusting screw 22 serves as a limit stop to define the oscillatory movement of the roller 12 upon engagement with the form or plate upon the cylinder 14, and will thus have a tendency to control the pressure between said roller and the form or plate upon the cylinder 14 as the carriage 10 reaches the limit of its movement toward said cylinder. The screw 36 will have the same effect as to the roller 13. The action as to each of these screws is supplemented by the set screws 26 and 37.

Since the adjustment of the inking rollers with relation to the printing surface is based upon the triangular relation of the axes of the distributing roller 11 and the inking rollers 12 and 13, and the capability of movement of the rollers 12 and 13 circumferentially of the roller 11, which will permit said inking rollers to adjust themselves or be adjusted to the curvature of the printing surface, it is apparent that a similar effect to that herein described might be secured by having the frames 20 and 32 so associated to act as a unit, although any nicety of the proportioning and the dimension of parts and the finishing thereof, is avoided by employing independently rotatable frames under independent controls for adjustment purposes. Furthermore this construction permits great nicety in the adjustment of the inking rollers with relation 120 125 130

to the printing surface and avoids any necessity for exactitude in the diameters of the inking rollers.

Having described the invention, what I claim as new and desire to have protected by Letters Patent, is:—

1. An inking mechanism for printing machines embodying therein a carriage adapted to have movement toward and from a form or plate cylinder, a distributing roller mounted therein, an inking roller associated with said distributing roller and adapted to be brought into and out of engagement with the form or plate upon said cylinder as determined by the movement of said carriage, means for imparting movement to said inking roller radially of said distributing roller to secure the proper relation of said rollers to each other, and means for imparting movement to said inking roller circumferentially of said distributing roller, and towards or from said form or plate cylinder to secure the proper relation of said inking roller to the form or plate, independently of said first named means.

2. An inking mechanism for printing machines embodying therein a carriage adapted to have movement toward and from a form or plate cylinder, a distributing roller mounted therein, a frame mounted to have rotatable movement about an axis concentric with that of said distributing roller, a bearing mounted upon said frame, means for imparting movement to said bearing radially of said distributing roller, an inking roller mounted in said bearing in engagement with said distributing roller, said inking roller being adapted to be brought into and out of engagement with the form or plate upon a cylinder with the movement of said carriage, and means for imparting movement to said frame circumferentially of said distributing roller to position said inking roller properly with relation to the form or plate, said last named means being operative independently of the means adjusting said inking roller.

3. An inking mechanism for printing machines embodying therein a carriage adapted to have movement toward and from a form or plate cylinder, a distributing roller mounted therein, a frame mounted to have rotatable movement about an axis concentric with that of said distributing roller, a bearing, supporting means for said bearing extending radially of said distributing roller, whereby said bearing is mounted upon said frame, means co-operating with said supporting means for imparting movement to said bearing radially of said distributing roller, an inking roller mounted in said bearing in engagement with said distributing roller, said inking roller being adapted to be brought into and out of engagement

with the form or plate upon a cylinder with the movement of said carriage, and means for imparting movement to said frame circumferentially of said distributing roller to position said inking roller properly with relation to the form or plate, said last named means being operative independently of the means adjusting said inking roller.

4. An inking mechanism for printing machines embodying therein a carriage adapted to have movement toward and from a form or plate cylinder, a distributing roller mounted therein, a frame mounted to have rotatable movement about an axis concentric with that of said distributing roller, bearings upon said frame, an inking roller bearing, a screw-threaded stem therefor mounted in said first named bearings, an adjusting nut carried by said screw-threaded stem between said bearings, whereby said inking roller bearing may have movement imparted thereto radially of said distributing roller, an inking roller mounted in said bearing in engagement with said distributing roller, said inking roller being adapted to be brought into and out of engagement with the form or plate upon a cylinder with the movement of said carriage, and means for imparting movement to said frame circumferentially of said distributing roller to position said inking roller properly with relation to the form or plate, said last named means being operative independently of the means adjusting said inking roller.

5. An inking mechanism for printing machines embodying therein a carriage adapted to have movement toward and from a form or plate cylinder, a distributing roller mounted therein, a frame mounted to have rotatable movement about an axis concentric with that of said distributing roller, a bearing mounted upon said frame, means whereby movement may be imparted to said frame radially of said distributing roller, an inking roller mounted in said bearing in engagement with said distributing roller, said inking roller being adapted to be brought into and out of engagement with the form or plate upon a cylinder with the movement of said carriage, and a screw carried by said carriage and acting upon said frame eccentrically of its axis, whereby movement may be imparted to said frame circumferentially of said distributing roller to position said inking roller properly with relation to the form or plate independently of the means adjusting said inking roller.

6. An inking mechanism for printing machines embodying therein a carriage adapted to have movement toward and from a form or plate cylinder, a distributing roller mounted therein, a frame mounted to have rotatable movement about an axis concentric with that of said distributing roller, bearings upon said frame, an inking roller

bearing, a screw-threaded stem therefor mounted in said first named bearings, an adjusting nut carried by said screw-threaded stem between said bearings, whereby movement may be imparted to said inking roller bearing radially of said distributing roller, an inking roller mounted in said bearing in engagement with said distributing roller, said inking roller being adapted to be brought into and out of engagement with the form or plate upon a cylinder with the movement of said carriage, and a screw carried by said carriage and acting upon said frame eccentrically of its axis, whereby movement may be imparted to said frame circumferentially of said distributing roller to position said inking roller properly with relation to the form or plate independently of the means adjusting said inking roller.

7. An inking mechanism for printing machines embodying therein a carriage adapted to have movement toward and from a form or plate cylinder, a distributing roller mounted therein a frame mounted to have rotatable movement about an axis concentric with that of said distributing roller, bearings upon said frame, an inking roller bearing a screw-threaded stem therefor mounted in said first named bearings, an adjusting nut carried by said screw-threaded stem between said bearings, whereby movement may be imparted to said inking roller bearing radially of said distributing roller, an inking roller mounted in said bearing in engagement with said distributing roller, said inking roller being adapted to be brought into and out of engagement with the form or plate upon a cylinder with the movement of said carriage, a screw carried by said carriage and acting upon said frame eccentrically of its axis, whereby movement may be imparted to said frame circumferentially of said distributing roller to position said inking roller properly with relation to the form or plate independently of the means adjusting said inking roller, said frame having an opening therein, and a set screw passing through said opening and engaging said carriage and said frame, whereby said frame may be set in any adjusted position.

8. An inking mechanism for printing machines embodying therein a carriage adapted to have movement toward and from a form or plate cylinder, a distributing roller mounted therein, a plurality of inking rollers associated with said distributing roller and adapted to be brought into and out of engagement with the form or plate cylinder as determined by the movement of said carriage, means associated with each of said inking rollers whereby movement may be imparted thereto radially of said distributing roller to secure the proper relation of each of said inking rollers to said distributing roller, and independently operative

means operative upon said inking rollers respectively, whereby movement may be imparted to either of said inking rolls circumferentially of said distributing roller, to ensure the proper relation of each of said inking rollers with the form of plate cylinder independently of the radial adjustment thereof.

9. An inking mechanism for printing machines embodying therein a carriage adapted to have movement toward and from a form or plate cylinder, a distributing roller mounted therein, a plurality of frames each capable of movement independent of the other about an axis concentric with that of said distributing roller, a bearing upon each of said frames, means for imparting movement to each of said bearings radially of said distributing roller, an inking roller mounted in each of said bearings in engagement with said distributing roller, said inking rollers being adapted to be brought into and out of engagement with the form or plate upon a cylinder with the movement of said carriage, and means for imparting movement to said frames respectively circumferentially of said distributing roller to position said inking rollers properly with relation to the form or plate, said last named means being operative independently of the adjusting means operative upon said inking rollers.

10. An inking mechanism for printing machines embodying therein a carriage adapted to have movement toward and from a form or plate cylinder, a distributing roller mounted therein, a plurality of frames each capable of movement independent of the other about an axis concentric with that of said distributing roller, a bearing upon each of said frames, supporting means for each of said bearings extending radially of said distributing roller, whereby said bearings are mounted upon said frames, means co-operating with said supporting means whereby either of said bearings may have movement imparted thereto radially of said distributing roller independently of the other, an inking roller mounted in each of said bearings in engagement with said distributing roller, said inking rollers being adapted to be brought into and out of engagement with the form or plate upon a cylinder with the movement of said carriage, and means for imparting movement to said frames respectively circumferentially of said distributing roller to position said inking rollers properly with relation to the form or plate, said last named means being operative independently of the adjusting means operative upon said inking rollers.

11. An inking mechanism for printing machines embodying therein a carriage adapted to have movement toward and from

- a form or plate cylinder, a distributing roller mounted therein, a plurality of frames each capable of movement independent of the other about an axis concentric with that of said distributing roller, a plurality of bearings upon said frames, inking roller bearings, a screw-threaded stem for each of said bearings mounted in said first named bearings respectively, an adjusting nut carried by each of said screw-threaded stems between said bearings, whereby said inking roller bearings may each have movement imparted thereto radially of said distributing roller, an inking roller mounted in each of said bearings in engagement with said distributing roller, said inking rollers being adapted to be brought into and out of engagement with the form or plate upon a cylinder with the movement of said carriage, and screws carried by said carriage and acting upon said frames respectively eccentrically of their axes, whereby movement may be imparted to each of said frames circumferentially of said distributing roller to position said inking rollers properly with relation to the form or plate cylinder. 80
- 5 10 15 20 25 30 35 40 45 50 55 60
12. An inking mechanism for printing machines embodying therein a carriage adapted to have movement toward and from a form or plate cylinder, a distributing roller mounted therein, a plurality of frames each capable of movement independent of the other about an axis concentric with that of said distributing roller, a bearing upon each of said frames, means for imparting movement to each of said frames radially of said distributing roller, an inking roller mounted in each of said bearings in engagement with said distributing roller, said inking rollers being adapted to be brought into and out of engagement with the form or plate upon a cylinder with the movement of said carriage, and screws carried by said carriage and acting upon said frames respectively eccentrically of their axes, whereby movement may be imparted to each of said frames circumferentially of said distributing roller to position said inking rollers properly with relation to the form or plate cylinder. 100
- 30 35 40 45 50 55 60
13. An inking mechanism for printing machines embodying therein a carriage adapted to have movement toward and from a form or plate cylinder, a distributing roller mounted therein, a plurality of frames each capable of movement independent of the other about an axis concentric with that of said distributing roller, a plurality of bearings upon said frames, inking
- 5 10 15 20 25 30 35 40 45 50 55 60
- roller bearings, a screw-threaded stem for each of said bearings mounted in said first named bearings respectively, an adjusting nut carried by each of said screw-threaded stems between said bearings, whereby said inking roller bearings may each have movement imparted thereto radially of said distributing roller, an inking roller mounted in each of said bearings in engagement with said distributing roller, said inking rollers being adapted to be brought into and out of engagement with the form or plate upon a cylinder with the movement of said carriage, and screws carried by said carriage and acting upon said frames respectively eccentrically of their axes, whereby movement may be imparted to each of said frames circumferentially of said distributing roller to position said inking rollers properly with relation to the form or plate cylinder. 80
